SHEET OF WRAPPING PAPER OR THE LIKE

James E. Donaldson, Chicago, Ill.

Application September 22, 1949, Serial No. 5,132

Term of patent 14 years

(Cl. D59—2)

To all whom it may concern:

Be it known that I, James E. Donaldson, a citizen of the United States, and resident of Chicago, in the county of Cook, and State of Illinois, have invented a new, original, and ornamented Design for a Sheet of Wrapping Paper or the like, of which the following is a specification, reference being had to the accompanying drawing, forming a part thereof.

In the drawing the figure is a face view of a sheet of wrapping paper, or the like, showing my new design.

I claim:

The ornamental design for a sheet of drawing paper or the like, as shown.

JAMES E. DONALDSON.
